UNITED STATES PATENT OFFICE.

J. WALTER SPALDING, OF NEW YORK, N. Y., ASSIGNOR TO A. G. SPALDING & BROTHERS, OF CHICAGO, ILLINOIS.

DESIGN FOR THE ORNAMENTATION OF GAME-TABLETS.

SPECIFICATION forming part of Design No. 18,411, dated June 26, 1888.

Application filed January 12, 1888. Serial No. 260,578. Term of patent 7 years.

To all whom it may concern:

Be it known that I, J. WALTER SPALDING, a citizen of the United States, and a resident of the city, county, and State of New York, have invented and produced a new and original Design for the Surface Ornamentation of Game-Tablets, of which the following is a specification, reference being had to the accompanying drawing, forming part thereof.

10 The present design is particularly adapted to the surface ornamentation of game-tablets of any suitable forms or materials, and in the accompanying illustration is illustrated in connection with a circular tablet.

15 The design as thus embodied has for its particular characteristic or leading feature a representation in connection with the game of base-ball; and, as therein delineated, it consists of the head and shoulders of a player—for instance, the pitcher—with his arm extended vertically from the shoulder and grasping in his hand a base-ball. The player, as shown, has a hat upon his head, and his extended arm is bared to the elbow, the garment being shown as rolled up to that part of the arm. 25 In the background is represented a portion of the ball-grounds, having the representation of part of a stand for the spectators, with foliage beyond the stand. The whole may be inclosed by a suitable border or not, as fancy may dictate.

What I claim is—

The design for the surface ornamentation of game-tablets, the same consisting in the representation of the shoulders, head, and extended arm of a player holding a ball in his hand, together with a background, substantially as shown and described. 35

In testimony whereof I have signed my name to this specification in the presence of two subscribers.

J. WALTER SPALDING.
